US0D1063982S

(12) **United States Design Patent** (10) Patent No.: **US D1,063,982 S**
(45) Date of Patent: ** *Feb. 25, 2025

(54) **DISPLAY SCREEN OR PORTION THEREOF WITH ICON**

(71) Applicant: **Waymo LLC**, Mountain View, CA (US)

(72) Inventors: **Peter Crandall**, San Jose, CA (US); **Nirmal Patel**, Sunnyvale, CA (US)

(73) Assignee: **Waymo LLC**, Mountain View, CA (US)

(*) Notice: This patent is subject to a terminal disclaimer.

(**) Term: **15 Years**

(21) Appl. No.: **29/803,214**

(22) Filed: **Aug. 11, 2021**

Related U.S. Application Data

(63) Continuation of application No. 29/623,844, filed on Oct. 27, 2017, now abandoned.

CLAIM

The ornamental design for a display screen or portion thereof with icon as shown and described.

DESCRIPTION

FIG. 1 is a front view of the claimed design for a display screen or portion thereof with icon;

FIG. 2 is a front view of an alternative embodiment of the claimed design for a display screen or portion thereof with icon;

FIG. 3 is a front view of an alternative embodiment of the claimed design for a display screen or portion thereof with icon;

FIG. 4 is a front view of an alternative embodiment of the claimed design for a display screen or portion thereof with icon;

FIG. 5 is a front view of an alternative embodiment of the claimed design for a display screen or portion thereof with icon;

FIG. 6 is a front view of an alternative embodiment of the claimed design for a display screen or portion thereof with icon;

FIG. 7 is a front view of an alternative embodiment of the claimed design for a display screen or portion thereof with icon; and,

FIG. 8 is a front view of an alternative embodiment of the claimed design for a display screen or portion thereof with icon.

The uneven-length broken line showing a display screen and the even-length broken lines showing elements of the graphical user interface illustrate portions of the article and form no part of the claimed design.

1 Claim, 4 Drawing Sheets
